A-SHAPED CHAIR

Frederick G. Kohl, Brooklyn Heights, and Robert K. Marceca, Chappaqua, N.Y., assignors to Rio Enterprises Incorporated, New York, N.Y.

Filed Aug. 6, 1970; Ser. No. 24,354

Term of patent 14 years

Int. Cl. D6—02

U.S. Cl. D6—12

FIG. 1 is a perspective view of an A-shaped chair showing our new design;

FIG. 2 is a side elevation of FIG. 1;

FIG. 3 is a front elevation of FIG. 1;

FIG. 4 is a rear elevation of FIG. 1;

FIG. 5 is a top plan view of FIG. 1; and

FIG. 6 is a bottom plan view of FIG. 1.

We claim:

The ornamental design for an A-shaped chair, substantially as shown and described.
